FUEL FEEDING TO RESONANCE TYPE JET PROPULSION ENGINES

Robert E. Houle, Willimantic, Conn.

Application April 2, 1952, Serial No. 279,979

19 Claims. (Cl. 60—39.28)

The present invention relates to jet propulsion engines, and is particularly directed to improved apparatus for feeding fuel to resonance type jet propulsion engines. This application is a continuation-in-part of my co-pending applications Serial No. 32,064, filed June 10, 1948, now abandoned; Serial No. 129,110, filed November 23, 1949; and Serial No. 238,173, filed July 23, 1951.

As set forth in the last mentioned of the above co-pending applications, the utilizable power output of existing jet propulsion engines, whether ram jets, turbine jets, internal reaction rocket motors or resonance jets, is never more than a relatively small fraction, often not more than 20 to 25%, of the theoretically calculated output thereof. The calculated theoretical output is determined as the difference between the energy that may be released in the complete molecular reaction of the combustible mixture involved and the sum of the energy necessary to initiate the molecular reaction and the heat of formation of the combustion and its products.

The great disparity heretofore existing between the energy actually obtained from a given quantity of the combustible mixture and the energy that one would expect to be made available by a complete molecular reaction has been explained as resulting from the fact that, what has been assumed to be a homogeneous combustion process, is in reality, in the chemical gas phase, only an incomplete reaction. During this incomplete reaction, the fuel molecules have random wave lengths and only a very small number of the fuel molecules in the combustible mixture are sufficiently excited and ionized to cause critical concentrations of dissociated atoms and radicles forming new combinations and leading to heterogeneous reactions in the gas phase which are of a superior type or order of reaction and effect the liberation of molecular energy. Further, when only a relatively few of the fuel molecules are sufficiently excited, the slower moving molecules, that is, those of greater wave lengths, have a tendency to damp out the effects of collisions between the few sufficiently excited molecules, and reactions of the superior type or order, effecting release of molecular energy, are thereby discouraged.

In order to provide an engine of the resonance jet type wherein a combustion reaction in the fuel gases of a superior order or type is obtained so that the actual power output of the engine closely approaches the theoretically calculated power output thereof, I have proposed, in my co-pending applications, identified above, that combustion of the fuel mixture be obtained by violent detonation, as distinguished from the relatively slow and incomplete combustion occurring in existing engines, with the violent detonation being caused by the production of shock waves within the jet tube of frequency and magnitude sufficient to effect dissociation of the fuel molecules to provide dissociated atoms and radicles in a reaction releasing molecular energy.

The excitation or activation of the fuel molecules in a combustible mixture may be achieved by a combination

2

of pressure and temperature. It is known that, for a given combustible mixture, there exist certain critical conditions which, upon their occurrence, change a relatively slow combustion into the desired violent detonation. As long as the pressure is relatively low, for example, of the order of one atmosphere or less, detonation only occurs at elevated temperatures, which may be of the order of from 500° to 1000° C. For higher pressures, the critical detonation temperatures are reduced, and, if a uniformly relatively low temperature is maintained while the pressure is varied, the initiation of detonations will coincide with the occurrence of high pressure peaks.

The mode of operation of any resonance jet engine is well understood insofar as it involves the transmission of a series of pulses or explosions along a tube, with the direct and reflected pulses meeting and coalescing to divide the tube into a series of vibrating parts, called "ventral segments," each separated from the next adjacent segments by points of apparent rest, called "nodes." Each nodal point is an area in which variable pressures are generated, and if the variable pressures reach sufficiently high values, at or near the peaks thereof, they may produce violent detonation of the combustible mixture introduced to the jet tube. In my co-pending applications, identified above, I have proposed that the production within the jet tube of shock waves of frequency and magnitude effecting violent detonation of the fuel molecules to provide dissociated atoms and radicals in a reaction releasing molecular energy may be obtained by rhythmically phasing the inflow of a combustible mixture to the combustion chamber at a frequency which is harmonically related to both the acoustic resonant frequency, or fundamental frequency, of the jet tube at operating conditions and the natural frequency of the fuel molecules during detonation, and in a manner to produce shock waves in the tube of amplitudes greater than approximately 140 decibels.

I have now found that, while the above mentioned conditions, set forth in detail in my co-pending applications, produce the desired violent detonation of the combustible mixture so that optimum efficiency is attained in utilizing the latent energy of the fuel molecules participating in the detonation, the attainment of maximum power output and fuel economy for a given resonance type jet engine requires still further control of the fuel admitted thereto. Thus, I have found it desirable, not only to control the overall proportions of fuel and air contained in the combustible mixture to obtain a mixture that is susceptible to being detonated at the peak pressures generated by the shock waves, but also to control the flow of the fuel component of the combustible mixture so that such flow is pulsating and the rate of fuel flow is related to the amplitude of the peak pressures occurring in the jet tube capable of producing detonation.

Accordingly, an object of the present invention is to provide apparatus for feeding fuel to a resonant jet engine of the described character, wherein the flow of fuel is pulsatingly synchronized with the pressure variations within the combustion chamber or jet tube so that the fuel component of the combustible mixture flows at a periodically varying rate effective to concentrate the fuel flow into intermittent bursts corresponding in quantity to the amplitude of the peak pressures in the combustion chamber.

Another object is to provide apparatus for feeding fuel to a resonant jet engine of the described character, wherein the pressure causing flow of the fuel component of the combustible mixture is varied in synchronism with the varying pressure in the combustion chamber or jet tube so that the rate of flow of fuel into the com-

bustion chamber is correspondingly varied in accordance with the pressure variations in the combustion chamber.

A further object of the present invention is to provide means for feeding a pulsating flow of fuel to the combustion chamber of a resonance jet engine of the described character, wherein the pulsations of the fuel are controlled in relation to the variable pressure in the combustion chamber and including provision for adjusting the influence of the variable pressure on the fuel flow.

A still further object of the present invention is to provide an arrangement for feeding fuel to a resonance jet engine of the described character wherein the fuel component of the combustible mixture is caused to flow in a pulsating manner related to the variable pressure produced in the combustion chamber or jet tube, and including means for controlling the influence of the variable pressure in the combustion chamber upon the characteristics of the pulsating fuel flow and means for controlling the rate of fuel flow.

A still further object of the present invention is to provide an arrangement for feeding fuel to a resonance jet engine of the described character as set forth in the preceding paragraph, and wherein the means for controlling the rate of fuel flow and the means for controlling the influence of the variable pressure upon the characteristics of the pulsating fuel flow are coordinated so that as the rate of fuel flow is increased the effectiveness of the variable pressure in the combustion chamber upon the fuel flow is reduced.

The above and other objects, features and advantages of the invention will be apparent in the following detailed description of illustrative embodiments thereof which is to be read in connection with the accompanying drawings, wherein:

Fig. 1 is an axial sectional view of a resonance jet engine having a fuel feeding assembly associated therewith which is constructed and arranged in accordance with the present invention;

Fig. 2 is an axial sectional view of another form of resonance jet engine having a fuel feeding assembly associated therewith which is constructed and arranged in accordance with another embodiment of the present invention;

Fig. 3 is an axial sectional view of still another form of resonance jet engine having the fuel feeding assembly of Fig. 2 associated therewith;

Fig. 5 is a graphic representation illustrating the fuel flow conditions for detonation in resonant jet engines of the described character;

Fig. 6 is a detail sectional view of a part of the fuel feeding assembly in Fig. 2 or Fig. 3; and

Fig. 7 is a graphic representation illustrating the relationship between the rate of fuel flow and the pressure in the combustion chamber for a fuel feeding arrangement embodying the present invention.

Referring to Fig. 1 of the drawing, a resonance jet engine is there shown of the kind that is fully described in my above-identified co-pending applications. This resonance jet engine includes a combustion chamber 25 having a jet tube 26a extending from the rear end thereof and a spark plug or igniter 65 extending into the combustion chamber for starting the engine. As described in my co-pending application, fuel from the tank 79 passes through the feed line 63, having a control valve 64 interposed therein, into a fuel nozzle 82. Nozzle 82 extends axially through the center of the air inlet head 88 and connects to the static fuel discharge head 84 which discharges the fuel radially into an intermediate air-fuel inlet section 85 where it is mixed with air entering through the apertures 87 of the air inlet head 88.

From the section 85, the air-fuel mixture enters into the central cavity 97 of the mixer head 86 and discharges

from the latter through the passages 94. The secured together elements 88, 85 and 86 are disposed within the streamlined cowl 81 and air enters the latter at the open front end 80 thereof. Such entering air flows into the aforementioned passages 87 of the air inlet head 88 and also through the annular space 81a defined between the cowl 81 and the head 88 for entrance into the passages 95 of the mixer head 94.

An air line 113 extends from the top of fuel tank 79 to the cowl 81 to communicate the air pressure in the latter to the surface of the fuel and has a control valve 114 interposed therein. Thus, when the air pressure in the cowl 81 is relatively high, as hereinafter indicated, the flow of fuel in line 63 will be encouraged, and when the air pressure in the cowl is lower than atmospheric pressure, as hereinafter indicated, the flow of fuel through line 63 will be halted. The radial tongues 105 and 108 of the valve plates secured to the rear face of mixer head 86 serve to control the flow of fluid out of the passages 95 and 94, respectively, of the mixer head. When an explosion in the combustion chamber 25 increases the pressure in the latter, the tongues 105 and 108 are seated against the open ends of the respective passages to stop the flow of fluid through the latter. When the pressure in the combustion chamber is decreased by movement of the gases therein toward the exhaust end of the jet tube 26a, the pressure in front of the tongues 105 and 108 becomes greater than the pressure behind the latter and the tongues are induced to move away from the ends of the respective passages to uncover the latter and permit flow therethrough. When air flows through the passages 95 of the mixer head, the pressure in line 113 is decreased to create a suction therein, while cessation of the flow through passages 95 results in an increase in the pressure in line 113. The pressure changes in the annular space within the cowl 81 and hence in the line 113 which opens radially into the cowl are produced as follows:

When the gases in chamber 25 are moving toward the exhaust end of the jet tube 26a, the area in the combustion chamber immediately in back of the tongues 105 and 108 is evacuated and attains a relatively low pressure less than that existing in front of the tongues to cause opening of the latter. When the tongues 105 and 108 open, the air and fuel mixture flows into the combustion chamber through the passages 94 and 95, from an area of relatively high pressure to an area of relatively low pressure. Thus, when the tongues are opened, a flow of air is induced through the cowl 81. Since the line 113 is a static head, in effect, the pressure in line 113 will drop as the velocity of flow through the cowl increases. When tongues 105 and 108 are again closed by the occurrence of the next detonation or peak pressure in the combustion chamber, the inertia of the air flow through the cowl 81 causes the air to continue to enter the cowl and to ram or build-up against the closed tongues for increasing the pressure within the cowl and sensed by the line 113.

It is to be understood that the variations in pressure within the cowl 81 are of the same frequency as the pressure peaks occurring within the combustion chamber and also that the amplitude or magnitude of the pressure changes occurring within the cowl 81, and hence sensed by the line 113, is proportional to the amplitude of the pressure peaks in the combustion chamber. That is, when the pressure peaks within the combustion chamber increase, the speed of the air flow through the cowl 81, with the tongues 105 and 108 open, is correspondingly increased to reduce the low pressure in the cowl, and, when the tongues are closed, the inertia of the increased air flow produces an increased ram effect in the cowl to increase the high pressures sensed by the line 113. Thus, as the peak pressures in the combustion chamber 25 are increased, the peak pressures acting on the surface of the fuel in tank 79 are similarly increased.

to increase the quantity of fuel contained in each burst or pulse from the nozzle 82. Since the amount of fuel that can be detonated is greater for relatively high peak pressures in the combustion chamber than for relatively low peak pressures in the combustion chamber, the above described action will always provide the greatest quantity of fuel in the combustion chamber that can be detonated by the peak pressures then occurring in the combustion chamber. Further, by properly selecting the lengths of the lines 113 and 63, and hence the time lag between the sensing of a pressure change at the end of line 113 and the corresponding change in the rate of fuel flow emitted from the nozzle 82, the phasing of the fuel pulses can be adjusted so that the fuel pulses occur when the tongues 105 and 108 are open.

The feeding of fuel to a resonance jet engine in the above manner has various advantages. First, it permits the accurate control of the proportions of the fuel-air mixture for each charge so that the necessary fuel-air mixture for violent detonation of each charge may be conveniently obtained. That is, the period and quantity of fuel flow into the mixing chamber is related to the character of the varying pressure in the combustion chamber. Further, greater fuel economy is obtained in that fuel flows from the tank 79 only in intermittent pulses which are related in character and in total quantity per pulse to the varying pressure in the combustion chamber.

Referring now to Fig. 2, another arrangement is shown for obtaining intermittent or pulsing fuel flow in association with a resonance jet engine of the type disclosed in my co-pending applications Serial No. 129,110, filed November 23, 1949; and Serial No. 238,173, filed July 23, 1951.

The resonance jet engine of Fig. 2 includes a combustion chamber 25 and jet tube 26a joined together and disposed within a jacket 21. The forward end of combustion chamber 25 is closed by a back plate 28a through which a cluster of air inlets, generally indicated by reference numeral 67a, extend. Each air inlet 67a includes a pipe 71 passing through plate 28a and having a flared forward end 72 to receive air entering at the front end of the jacket 21 and flowing through the latter in the direction of the arrows on Fig. 2. The rear end of each pipe 71 is cut on an angle, as at 73, and a resilient fin or vibrating membrane 78 is supported to overlie the rear inclined end of the pipe.

Fuel is admitted to the combustion chamber 25 through an axially extending pipe 63a which projects through the center of back plate 28a and carries a nozzle 62 at its end within the combustion chamber. In accordance with the present invention, the fuel flowing through the pipe 63a is made to pulsate in accordance with pressure variations within the combustion chamber. Accordingly, a section of fuel supply line 63b, extending from the tank 79a and having a valve 64 interposed therein, is connected to the inlet port of a fuel pump assembly, generally indicated by the numeral 125 and shown in detail in Fig. 6, while another section of the fuel supply line 63 extends from the outlet port of the fuel pump assembly to the fuel supply pipe 63a.

As seen in Fig. 6, the fuel pump assembly 125 includes a cylinder 126 having a piston 127 reciprocable therein. A check valve 128 is positioned at the inlet port of cylinder 126 to permit flow through said inlet only in the direction from tank 79a toward the cylinder, while another check valve 129 is located at the outlet port of cylinder 129 to permit flow therethrough only in the direction from said cylinder toward the pipe 63a. An actuating cylinder 130, having a piston 131 slidable axially therein, is arranged in axial alignment with cylinder 126 and a connecting rod 132 connects the pistons 127 and 131. A pipe or conduit 133 opens into cylinder 130 at the side of piston 131 remote from cylinder 126 and connects to the combustion chamber 25 of the associated

resonance jet engine. When the pressure in the combustion chamber varies, the pipe 133 communicates such pressure changes to the cylinder 130 for action against the piston 131. Thus, when an explosion or detonation occurs in the combustion chamber, the resultant high pressure causes the piston 131 to move to the left, as viewed in Fig. 6, and the connecting rod 132 serves to similarly move the piston 127 of the fuel pumping assembly 125. When a low pressure or suction is created in the combustion chamber, by the movement of the products of combustion in the direction of the arrows on Fig. 2 toward the open end of the jet tube, that suction acts on the piston 131, through the pipe or conduit 133, to move piston 131 toward the right, as viewed in Fig. 6, and the piston 127 similarly moves in the same direction. During movement of piston 127 to the right, as above, that is, the suction stroke, valve 128 is opened and valve 129 is closed to draw a charge of fuel from tank 79a through line 63b and valve 64 into cylinder 126. When piston 127 subsequently moves to the left, as viewed in Fig. 6, that is, during the pumping stroke, valve 128 is closed and valve 129 is opened, so that the fuel charge is pumped through fuel line 63 and pipe 63a for discharge through the nozzle 62 into combustion chamber 25. It is apparent that, during a pumping stroke of piston 127, the speed of movement of the latter will vary in accordance with the increasing and then decreasing pressure in combustion chamber 25 so that the piston 127 travels at a variable speed which is proportional to varying pressure in the combustion chamber. Further it is apparent that the rate of discharge of the fuel through nozzle 62 will vary in accordance with the speed of movement of piston 127 so that the rate of fuel discharge into the combustion chamber varies in accordance with the pressure developed in the latter. Referring to Fig. 7, wherein the solid line represents the pressure in the combustion chamber during successive operating cycles and the broken lines represent the rate of fuel flow during each successive cycle with fuel feeding device constructed in accordance with Figs. 2 and 6, it will be noted that fuel is discharged into the combustion chamber for each of the periods of pressure p and that the fuel flow is interrupted for a period corresponding to the time that a suction s is developed in the combustion chamber. Further, it will be noted that the maximum rate of fuel flow f is proportional to the amplitude of the peak pressure. Since the pressure required to detonate a lean fuel-air mixture is less than the pressure required to detonate a rich mixture, the above described coordination between the rate of fuel flow and the pressure in the combustion chamber ensures that the mixture supplied to the combustion chamber has a richness which is proportional to the peak pressures developed in the combustion chamber so that violent detonation of substantially all the fuel molecules may be achieved. Thus, the improved power output or efficiency associated with violent detonation of the fuel, as compared with relatively slow combustion thereof, is achieved with respect to all of the fuel molecules, so that the overall efficiency is enhanced. Further, since the greater power output is achieved with respect to all of the fuel molecules, a given power output may be realized with a smaller fuel consumption.

It should also be noted that the relationship between the rate of fuel flow and the pressure in the combustion chamber illustrated in Fig. 7, permits the operation of the associated resonance jet engine in a manner to obtain peak power output from the latter. Since the high rate of fuel flow occurs when the entry valves to the combustion chamber, for example, the tongues 105 and 108 of Fig. 1, are at their maximum open position, the total volume of fuel admitted to the combustion chamber during a pressure phase, represented by the area under line f , may be greater than the volume of fuel that could be admitted, under conditions obtaining detonation, if the fuel flow is at a substantially constant rate. That is, with

a substantially constant rate of discharge of fuel into the combustion chamber during a pressure phase, the rate of discharge cannot be greater than that providing a detonatable mixture for the conditions of less than peak pressure at the beginning and end of the pressure phase. Thus, at the peak pressure, the fuel mixture is leaner than required in order that it may be sufficiently lean during the periods when less than peak pressure is present. Accordingly, it is apparent that a substantially constant rate of fuel flow during the pressure phase requires the discharge of less than the maximum volume of fuel that may be detonated with the peak pressure involved, while varying the rate of fuel flow in accordance with the present invention permits the detonation of the maximum volume of fuel with a corresponding maximum power output.

Since the pressure developed in the combustion chamber controls the rate of fuel discharge from the nozzle 62, that rate of fuel flow will progressively increase with each successive pressure phase. That is, each discharge of fuel at the varied rate necessary for violent detonation provides a pressure peak greater than the highest pressure in the preceding pressure phase so that the fuel flow progressively increases to increase the power output up to an optimum value. However, when the rate of fuel flow exceeds that providing the optimum power output, further increases in fuel flow tend to discourage violent detonation with consequent loss in power output and efficiency.

In order to prevent increase of the rate of fuel flow beyond that value providing optimum power output, the assembly illustrated in Fig. 6 includes structure for limiting the length of stroke of piston 127. This structure includes a collar 134 fixed on the connecting rod 132 and engageable against an adjustable stop 135. Stop 135 has a worm shaft 136 extending threadably therethrough, with the shaft 136 being rotatably supported in suitable brackets 137 and having an actuating crank 138 on one end thereof. Rotation of stop 135 is prevented by suitable structure, for example, the illustrated rod 139 on which the stop is slidable. Thus, rotation of screw shaft 136 displaces the stop 135 to vary the permitted stroke of collar 134 and hence of piston 127. By controlling the stroke of piston 127, the volume of fuel admitted to the combustion chamber may be adjusted to the volume providing a stabilized condition of optimum power output.

While the tendency of the arrangement in Fig. 6 is to progressively enrich the fuel-air mixture, the first described embodiment of Fig. 1 tends to progressively lean out the combustible mixture as the power output increases. That is, as the speed of the air entering passages 95 increases during the intervals between successive pressure phases in the combustion chamber, the suction in line 113 similarly increases to more completely interrupt the fuel flow through line 63. Thus, merely opening valve 64 in the fuel line to supply greater quantities of fuel for the increased power output will not prevent a starving tendency resulting from the action of the suction in line 113. For that reason, a valve 114 is provided in the suction line 113 and, as the fuel supply valve 64 is progressively opened, the suction controlling valve 114 is progressively closed.

In Fig. 4, I have illustrated a simple device for simultaneously effecting manipulation of the valves 64 and 114. This device 140 includes a disc 141 having an actuating handle 142 extending therefrom and mounted for rotation on the pivot 143. The valve member of valve 114 has an arm 144 extending therefrom which is pivotally connected to one end of a link 145 having its other end pivotally connected, as at 146, to a suitable location on the disc 141. The valve member of valve 64 similarly has an arm 147 extending therefrom for connection to a link 148 which is attached to disc 141, as at 149. The disc 141 is formed with series of openings for

attachment of the links 145 and 148 thereto so that the differential movements of the valves 64 and 114 may be adjusted as desired. As illustrated, the disc 141 may be provided with a pointer 150 which cooperates with a suitably calibrated scale 151 to indicate the conditions of valves 64 and 114. With the device of Fig. 4, the influence of the suction in line 113 on the fuel flow may be reduced as the suction increases with increasing power output so that the mixture will not be leaned-out beyond the value at which violent detonation may be achieved.

In order to further control the effectiveness of the suction or low pressure induced in line 113 in influencing the flow of fuel through line 63 in the embodiment of Fig. 1, provision is made for varying the volume of air disposed above the fuel level in tank 79. Variation of the volume of air disposed above the fuel in tank 79 is obtained in the illustrated embodiment by providing the tank with a vertically movable top wall 79a through which the line 113 projects. Adjustment of the position of top wall 79a may be effected by any suitable mechanism, for example, the simple arrangement shown in Fig. 1, which includes a lever arm 152 pivoted adjacent its center on a suitable support 153 and connected at one end to the tank wall 79a by a link 154. A handle 155 may be provided at the other end of lever 152, and a perforated quadrant 156 may be disposed adjacent to the lever to receive a pin carried by the latter for retaining the lever and tank top wall in adjusted position.

When starting the engine, top wall 79a of the tank is adjusted to provide a small space above the surface of the fuel therein so that the variations in pressure in line 113 will be immediately felt within the tank to influence the fuel flow through line 63. As the engine approaches its normal operating condition, and the variations in the pressure in line 113 become more pronounced, the space above the fuel may be enlarged so that a reduced pressure in line 113 is only partially felt in the tank and the "starving-out" heretofore referred to may be controlled or eliminated.

Referring to Fig. 5, the relationship between fuel consumption and the pressure developed in the combustion chamber is there illustrated. The lines *a* and *b* representing the pressure slope and the constant detonation slope cross or intersect at the point *c*, which point corresponds to the production of the peak pressure, as indicated by the dotted line. With the arrangement of Fig. 1, the engine is started in the extreme rich condition, and the mixture is leaned out in the direction of arrow 152 until detonation is achieved. The suction in line 113 then automatically serves to further lean-out the mixture until the peak pressure is obtained and this condition is then stabilized with the control arrangement of Fig. 4. With the fuel feeding arrangement of Figs. 2 and 6, the resonance jet engine is started in the extreme lean condition and the mixture is enriched in the direction of arrow 153 of Fig. 5 until it is sufficient to sustain combustion. The pump 125, operated by the varying pressure in the combustion chamber, then serves to further enrich the mixture until the peak pressure of violent detonation is achieved, and that condition is stabilized by the adjustable stop 135 for limiting the stroke of the piston 127.

Referring now to Fig. 3, a fuel feeding arrangement of the kind shown in Figs. 2 and 6 is there shown associated with a resonance jet engine of the type described in my co-pending application Serial No. 238,173, filed July 23, 1951. This resonance jet engine includes an outer tube or jacket 21 having a concentric combustion chamber 25 therein communicating with a rearwardly extending jet tube 26 through an intermediate stepdown section 27. The forward end of the combustion chamber is closed by a rearwardly concave back plate 28. A forwardly opening, bell-shaped member 115 is supported in jacket 21 ahead of the combustion chamber by structure which includes horizontal arms 118 and a vertical streamlined spar 117 and is intended to receive air entering at the front end of the jacket 21 and flowing through

the latter in the direction of the arrows on Fig. 3. A fuel supply line 119 extends into spar 117 and the latter is formed with discharge openings 120 at the trailing edge thereof to discharge fuel into the member 115. A series of flexible pipes 122 extend from openings in the rear portion of member 115 to carry the fuel-air mixture to associated injector assemblies 123 which are constructed and arranged to discharge a phased fuel-air mixture into the combustion chamber through related openings in the back plate 28.

As set forth in my above identified co-pending application, the injectors 123 are operated by the explosions in the combustion chamber to propel the fuel-air mixture into the latter. Since the injectors 123 form no part of the present invention, the construction thereof will not be described in detail. However, it may be noted, generally, that each of the injectors 123 includes an impeller which is arranged to be rotatably driven by the back pressures accompanying detonations in the combustion chamber, and the rotated impeller in turn pumps the fuel air mixture into the combustion chamber. As seen in Fig. 3, the fuel line 119 is connected to the outlet port of the pumping cylinder assembly 125a which is the same as the assembly 125 in the device of Figs. 2 and 6. The piston of the assembly 125a is operated by a connecting rod 132a extending from the piston in an actuating cylinder 130a while the piston in the latter moves in response to the pressure variations in combustion chamber 25 by reason of the conduit 133a communicating cylinder 130a with the combustion chamber. Thus, the rate of fuel flow through line 119 and the quantity of fuel included in each pulse will be controlled by the pressure peaks in the combustion chamber.

The engine of Fig. 3, as in the case of the engine in Fig. 2, is started with an extremely lean mixture, and the fuel feeding arrangement serves to increase the richness of the mixture as the power increases. Accordingly, means similar to the stop 135 of Fig. 6 are associated with the connecting rod 132a to limit the stroke of the fuel pumping piston so that the mixture may be stabilized at the condition producing violent detonation of the fuel.

From the foregoing it is apparent that the present invention provides means for feeding a pulsing flow of fuel to resonance jet engines of the described character wherein the rate of fuel flow is related to the varying pressure produced in the combustion chamber so that the maximum rate of fuel flow coincides with the occurrence of the peak pressure to thereby provide a mixture which is susceptible to violent detonation at all stages of the pressure phase. Further, it is apparent that devices have been provided for adjusting the influence of the combustion chamber pressure upon the rate of fuel flow so that the latter may be maintained in a stabilized pattern producing violent detonation of the fuel for effecting a reaction forming dissociated atoms and radicles and releasing molecular energy.

While I have described and illustrated several specific embodiments of my invention, it should be noted that the invention is not limited to these precise embodiments, and that changes and modifications may be made therein without departing from the scope of the invention as defined in the appended claims.

What I claim is:

1. In a resonance jet engine; the combination of an elongated tube defining a combustion chamber at one end, means defining a mixing chamber, means defining passages communicating said mixing chamber with said combustion chamber, means for supplying fuel to said mixing chamber, means for supplying air to said mixing chamber, and valve means in said passages responsive to the pressures at said one end of the tube to open and close at a frequency which is harmonically related to the natural frequency of the fuel molecules and to the fundamental frequency of said tube so that the mixture of air and fuel fed through said passages produces a standing

shock wave in said tube, pressure responsive means connected to control said fuel supply means to provide a pulsing flow of fuel having periods of flow at the same frequency as the occurrence of elevated pressures in said combustion chamber and quantities proportional to the amplitude of the elevated pressures.

5 2. In a resonance jet engine; the combination according to claim 1, wherein said fuel supply means includes fuel pumping means, and actuating means operatively connected to said pumping means for actuating the latter in response to elevated pressures in said combustion chamber.

10 3. In a resonance jet engine; the combination according to claim 2, wherein said fuel supplying means includes a fuel feeding line extending from said source, said pumping means being interposed in said line and including a linearly movable piston, and said actuating means including a cylinder having a piston reciprocatable therein, means connecting the last mentioned piston with said 15 pumping piston and a conduit communicating said combustion chamber with said cylinder so that the piston in the latter is displaced in one direction in response to an elevated pressure in said chamber and in the opposite direction in response to a reduced pressure in said chamber, the speed of displacement of said actuating piston and of said pumping piston being proportional to the rate of increase of the elevated pressures in said chamber so that the rate of fuel flow through said fuel feeding line in response to the occurrence of said elevated pressures 20 varies in accordance with the rate of increase of said elevated pressures.

30 4. In a resonance jet engine; the combination according to claim 3, including means for varying the influence of the elevated pressures in said chamber upon the quantity of fuel discharged by said pumping means during each stroke of the piston thereof.

40 5. In a resonance jet engine; the combination according to claim 4, wherein the last mentioned means includes an adjustable stop and a member movable with said pumping piston and engageable against stop to limit the length of the stroke of said pumping piston.

6. In a resonance jet engine; the combination according to claim 1, wherein said air supplying means operates to provide a high speed air flow through said mixing chamber during periods of reduced pressure in said combustion chamber and a relatively low speed air flow through said mixing chamber during periods of elevated pressure in said combustion chamber, and wherein said means providing a pulsing flow of fuel operates in response to the pressure in the pulsing air flow to provide a rate of fuel flow varying inversely with said pressure in the pulsing air flow.

7. In a resonance jet engine; the combination of an elongated tube defining a combustion chamber at one end, means for supplying fuel to said combustion chamber including a fuel tank and a fuel feeding line extending from said tank for the gravity induced flow of fuel therethrough, means for supplying a pulsing flow of air to said combustion chamber and operative to provide a high speed air flow during periods of reduced pressure in said chamber and a relatively low speed air flow during periods of elevated pressure in said chamber at a frequency which is harmonically related to the naturally

65 frequency of the fuel molecules and to the fundamental frequency of said tube to produce a standing shock wave in said tube, and means providing a pulsing flow of fuel including an air line opening at one end at the air flow to sense the pressure in the latter and communicating with said tank above the fuel in the latter so that the pressure 70 acting on the fuel in the tank varies in accordance with the pressure in the air flow to alternately retard and advance the gravity induced flow of fuel through said fuel feeding line at the same frequency as the occurrence of elevated pressures in said combustion chamber.

75 8. In a resonance jet engine; the combination accord-

11

ing to claim 7, including means for adjusting the influence of pressure variations in the air flow upon the rate of fuel flow through said fuel feeding line.

9. In a resonance jet engine; the combination according to claim 8, wherein the last mentioned means includes a first valve interposed in said air line for restricting the latter.

10. In a resonance jet engine; the combination according to claim 9, wherein said fuel supplying means includes a second valve interposed in said fuel feeding line to vary the rate of fuel flow through the latter, and including means operatively connecting said first and second valves for progressively closing said first valve as said second valve is opened.

11. In combination; a resonance jet engine having a combustion chamber, a mixing chamber communicating with said combustion chamber, valve means between said mixing and combustion chambers operating at the frequency of pressure variation in the combustion chamber to open and close the communication between said chambers, means for supplying air to said mixing chamber, means supplying a pulsing flow of air to said combustion chamber at a frequency operative to acoustically produce intermittent elevated pressures in said combustion chamber, and means for supplying a pulsing flow of fuel to said mixing chamber at a rate of flow which varies at the same frequency as the acoustically produced intermittent elevated pressures and is volumetrically proportional to the amplitudes of said elevated pressures.

12. The combination according to claim 11; wherein said means supplying air to the combustion chamber operates to provide a rate of air flow varying substantially inversely with the pressure in said combustion chamber, and wherein said fuel supplying means includes a device sensitive to the pressure in the air flow to said combustion chamber.

13. In combination; a resonance jet engine having a combustion chamber, means supplying a pulsing flow of air to said combustion chamber at a frequency operative to acoustically produce intermittent elevated pressures in said chamber, with the rate of air flow varying substantially inversely with the pressure in said combustion chamber, and means for supplying a pulsing flow of fuel to said chamber at a varying rate of flow having its maximum coinciding with the occurrence of maximum pressure in said chamber, said fuel supplying means including a tank for containing a supply of fuel and a fuel feeding line extending from said tank to gravitationally conduct fuel to said engine, and a device sensitive to the pressure in the air flow including an air line disposed so that the pressure therein varies in accordance with the pressure in the air flow and connected to the top of said tank so that the variations of pressure in the air flow are communicated to the surface of the fuel supply to influence the rate of fuel flow through said fuel feeding line.

14. The combination according to claim 13; including first means for adjustably restricting said air line to vary the influence of the pressure in the air flow upon the rate of fuel flow through said fuel feeding line.

15. The combination according to claim 14; including second means for adjustably restricting said fuel feeding line to vary the rate of fuel flow through said fuel feeding line, and means operatively connecting said first and second restricting means so that, as said second restricting means is adjusted in the direction for increasing fuel flow through the fuel feeding line, said first restricting means

12

is simultaneously adjusted to increase the restriction of said air line.

16. The combination according to claim 11; wherein said fuel supplying means includes a fuel feeding line, pumping means interposed in said fuel feeding line for effecting the flow of fuel through the latter, and pump actuating means responsive to the pressure in said combustion chamber to operate said pumping means so that the latter produces flow through said fuel feeding line in response to the occurrence of elevated pressures in said chamber and at a rate varying in accordance with such elevated pressures.

17. The combination according to claim 16; wherein said pump actuating means includes a cylinder having an actuating piston therein, a line opening at its opposite ends into one end of said cylinder and into said combustion chamber so that the varying pressures in the latter effect reciprocation of said piston, and means operatively connecting said piston to said pumping means so that movement of said piston in one direction draws a fuel charge into said pumping means and movement of said piston in the opposite direction effects discharge of the fuel charge through the fuel feeding line.

18. The combination according to claim 17; wherein said pump actuating means further includes adjustable means for limiting the stroke of said piston so that the quantity of fuel discharged from said pumping means for each stroke of said piston in said opposite direction may be controlled independently of the pressures in said combustion chamber.

19. In a resonance jet engine the combination of an elongated tube defining a combustion chamber at one end, means for supplying a pulsing flow of air to said chamber and operative to provide a high speed air flow during periods of reduced pressure in said chamber and a relatively low speed air flow during periods of elevated pressure in said chamber, means for supplying fuel to said chamber including a fuel tank and a fuel feeding line extending from said tank for the gravity induced flow of fuel therethrough, means providing a pulsing flow of fuel including an air line opening at one end into the air flow to sense the pressure in the latter and communicating with said tank above the surface of the fuel in the latter so that the pressure in the space of said tank above the fuel varies in accordance with the pressure in the air flow to alternately retard and advance the gravity induced flow of fuel through said fuel feeding line, and means for adjusting the volume of said tank to thereby vary the space above the surface of the fuel so that the influence of the pressure in the air flow upon the flow of fuel may be controlled.
